UNITED STATES PATENT OFFICE.

WILLIAM JOHNSON STREALY, OF LEWISBURG, WEST VIRGINIA, ASSIGNOR OF ONE-THIRD TO W. T. ANDERSON, OF LEWISBURG, WEST VIRGINIA.

TOOL.

993,207.

Specification of Letters Patent.

Patented May 23, 1911.

Application filed October 20, 1910. Serial No. 588,174.

To all whom it may concern:

Be it known that I, WILLIAM JOHNSON STREALY, a citizen of the United States, and a resident of Lewisburg, in the county of 5 Greenbrier and State of West Virginia, have invented a new and Improved Tool, of which the following is a full, clear, and exact description.

This invention relates to a new and improved tool to be used as an attachment for 10 a mowing machine or reaper, whereby various operations can be performed in the field, such as removing knife sections, punching out rivets, straightening section bars and the 15 like, without the necessity of returning to the shop.

An object of this invention is to provide a device which ordinarily can be carried by 20 inserting the handle thereof on the pole of the reaper or mower, and which, when it is desired to use the same, can be readily clamped onto the wheel of the machine and utilized to great advantage.

A further object of this invention is to 25 provide a device which will be simple in construction, inexpensive to manufacture, exceedingly strong and durable, and readily attachable and detachable.

These and further objects, together with 30 the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a vertical section on the line 1—1 of Fig. 2; Fig. 2 is a top plan view, 40 showing the device attached to the rim of a mower or reaper wheel; Fig. 3 is a vertical section on the line 3—3 of Fig. 2; and Fig. 4 is a detail view of a preferred form of handle.

By reference more particularly to the separate parts, it will be seen that the device is very simple and comprises practically three separate pieces, which are the body portion 1, the clamp lever 2, and a bolt or 45 pin 3 for pivotally securing the clamp lever to the body portion. The body portion 1 is in the form of an anvil having a smooth upper surface for the greater portion there-

of, whereby a considerable amount of pounding can be accomplished thereon. This body 55 portion, however, is provided with a groove 4, in which may be set the section bar of a mowing machine or reaper, when it is desired to straighten the same or perform any other operation thereon. Within this groove 60 4, there is also provided a triangular depression 5, which may be used to knock out rivets, or for any other suitable purpose. On one end of the top or anvil portion of the body 1, there is also provided a recess 65 6, which may be utilized to leave room to knock out rivets from the cutter bar of a mowing machine, or for any other suitable purpose.

On the side of the body portion 1, there 70 is provided a bracket 7, which is spaced apart from the body portion to form a slot 8, in which may be inserted one of the sections of the cutter bar when it is desired to sever the rivets so as to remove one of the 75 sections from the section bar. The outer sides of this bracket 7 are preferably sloping, as at 9, so as to permit the wider portions of the knife sections to come in comparatively close juxtaposition to the 80 bracket without detracting from the strength thereof.

It will be noted that there is provided on one side of the body portion 1, a flange 10, having a slot 11 therein, through which extends the clamping lever 2, which is pivotally connected to an extension of the flange by means of the pivot pin or bolt 3. This clamping lever is provided with a handle 12 and a cam 13 gradually increasing in dimensions and projecting from one end of the handle. The cam 13 is adapted to engage under the rim 14 of a wheel on the reaper or mowing machine and aid in securing the tool to the wheel. For the purpose of further security, the body portion 1 is provided with a flange 15, extending parallel to the flange 10 and provided with a lug 16 adapted to engage under the rim 14.

The clamping lever 2 may be connected to 100 the body portion 1 by means of the pivot 3 extending through a single circular opening therein, but it is preferable that the clamping lever 2 be adjustable relative to the body portion, so as to allow for the different sizes of wheels. For this purpose, it is

provided with a slot 17, having a plurality of recesses 18 arranged on opposite sides of the slot 17 and in staggered relation with respect to each other.

- 5 The operation of the device will be readily understood when taken in connection with the above description. When it is desired to remove a section knife from the cutter bar, the knife is inserted in the slot 10 8, and the section bar rested on the top of the anvil. By use of a hammer or monkey-wrench, a few blows on the section knife will sever the rivets connecting the section knife with the section bar. These rivets can 15 readily be punched out by placing them over the depression 5 or the recess 6. If it is desired to straighten the section bar, it may be placed in the groove 4 and readily trued up.
- 20 It will thus be seen that there is provided a simple and efficient tool which can readily be attached to and detached from wheels of various sizes, and thus enable a number of repairs to be made in the field, which would 25 ordinarily have to be done in the shop.

While I have shown one embodiment of my invention, I do not wish to be limited to the specific details thereof, but desire to be protected in various changes, modifications 30 and alterations which may come within the scope of the appended claims.

Having thus described my invention, I

claim as new and desire to secure by Letters Patent:—

1. The combination with a body portion 35 offering an anvil working surface, said body portion having flanges extending from opposite sides, forming a channel therebetween whereby said body portion is adapted to engage the rim of a wheel, of a lug on 40 one of said flanges, and a clamping lever on the other of said flanges having a gradually-increasing cam adapted to engage under the rim of the wheel, said clamping lever being adjustably connected to said body portion, so 45 as to allow for different sizes of wheels.

2. The combination with a body portion offering a working surface, of a clamping lever adapted to secure said body portion to the rim of a wheel, said clamping lever having a cam thereon and also having a slot 50 therein, said slot having recesses on opposite sides arranged in staggered relation, and a pivot adapted to engage said recesses 55 for pivotally securing said clamping lever to said body portion.

In testimony whereof I have signed my name to this specification in the presence of two subscribing witnesses.
